(57) **CLAIM**

(21) Appl. No.: **29/121,103**

We claim the ornamental design for a global positioning
system antenna housing, as shown.

(22) Filed: **Mar. 30, 2000**

DESCRIPTION

(51) **LOC (7) Cl. 14-03**

FIG. 1 is an upper left rear perspective view, of the global
positioning system antenna housing comprising the present
invention;

(52) **U.S. Cl. D14/231**

FIG. 2 is a bottom right front perspective view thereof;

(58) **Field of Search D14/230-238;**

FIG. 3 is a front elevational view thereof;

343/872, 702

FIG. 4 is a right side elevational view thereof;

2,942,265 * 6/1960 Ratkevich 343/872

FIG. 5 is a rear elevational view thereof;

D. 363,935 * 11/1995 McGreevy D14/230

FIG. 6 is a left side elevational view thereof;

D. 421,439 * 3/2000 Giuntoli D14/230

FIG. 7 is a top plan view thereof; and,

D. 427,996 * 7/2000 Heiligenstein et al. D14/230

FIG. 8 is a bottom plan view thereof.
